OIL CUP

Wallace E. Cutler, Franklin, N. H.

Application April 17, 1944, Serial No. 531,418

5 Claims. (Cl. 184—1)

This invention relates to an oil cup and it is one object of the invention to provide an oil cup with a container for catching surplus oil and thus prevent loss of oil due to filling a cup too full or due to oil backing up from a bearing to which it is supplied from the cup.

Another object of the invention is to so form the container for surplus oil and so connect it with the oil cup that it may receive overflowing oil either from within the cup or externally thereof in case the overflow pipe in the cup should become plugged or the cup suddenly filled to overflowing when replenishing the supply of oil therein.

Another object of the invention is to provide a device of this character which is simple in construction, cheap to manufacture, and so formed that the container may be easily removed for emptying oil therefrom and then replaced.

The invention is illustrated in the accompanying drawing wherein:

Figure 1 is a view showing the improved oil cup partially in vertical section and partially in elevation.

Figure 2 is a top plan view of the container for overflowing oil.

The oil cup 1 may be of any desired size and has its open top normally closed by a cap 2 which is hinged at 3 so that it may be swung upwardly to an opened position when the supply of oil in the cup must be replenished. A discharge nipple 4 extends laterally from the lower end of the cup and has its outer end portion threaded, as shown at 5, in order that the nipple may be screwed into the oil inlet of a bearing 6 indicated by dotted lines in Figure 1.

An overflow pipe 7 is disposed vertically in the oil cup with its lower portion passing through the bottom thereof and projecting downwardly an appreciable extent. The upper end of this pipe terminates in downwardly spaced relation to the open top of the oil cup. Therefore if oil is expanded in the cup by heat or back pressure or too much oil is poured into the cup, the surplus oil may flow downwardly through the overflow pipe 7 and into a container suspended in a vertical position from the lower end of the pipe. This container may be of any size desired and at its top is provided with a head 9 surrounded by an upstanding wall 10 which fits snugly into the container and is firmly secured therein in any desired manner. Since the head is countersunk within the upper end of the container it may serve as a basin to catch oil which may overflow externally from the oil cup in case the pipe 7 becomes clogged or oil is suddenly poured into the cup to such an extent that it flows outwardly over the upper end of the cup. A plurality of perforations 11 are formed through the head so that oil flowing from the cup into the basin defined by the coun-

tersunk head may drain therefrom into the container. An internally threaded boss or collar extends upwardly from the center of the head and when this collar is screwed onto the lower end of the pipe the container will be suspended from the pipe. When it is considered that a sufficient quantity of oil has collected in the container it is merely necessary to unscrew the container from the pipe and oil in the container may be poured out through the neck or collar and also through the openings 11 into a suitable receptacle, the container being then screwed onto the overflow pipe.

I claim:

1. An oil cup open at its top, a cap movable into and out of closing relation to the open top of said cup, a tubular nipple extending laterally from the bottom of said cup and threaded for engagement in a bearing, an overflow pipe extending vertically in said cup and through the bottom thereof and having its lower end threaded, the upper end of said pipe being spaced downwardly from the top of said cup, and a container for receiving and storing overflowing oil disposed vertically below said cup and having a depressed perforated head provided at its center with an opening surrounded by an upstanding collar internally threaded and screwed upon the lower end of said pipe to suspend the container from the pipe.

2. An oil cup open at its top and having a nipple extending from its bottom for engagement with a bearing, an overflow pipe disposed vertically in said cup and passing through the bottom thereof, a container under said cup, a perforated head for said container surrounded by an upstanding wall, and a collar carried by said head about an opening therein engaged with the lower end of said pipe to suspend the container from the pipe.

3. An oil cup adapted to be connected with a bearing, an overflow pipe extending vertically in said cup and through the bottom thereof, and a container under said cup having a depressed perforated head at its top formed with an opening surrounded by an upstanding collar threaded to the lower end of said pipe to suspend the container from the pipe.

4. An oil cup adapted to be filled through its top, an overflow pipe extending vertically in said cup and through the bottom thereof, and a container carried by and suspended from the lower end of said pipe and having a pipe engaging head at its top formed with a plurality of perforations and surrounded by an upstanding marginal wall.

5. An oil cup open at its top and having an outlet nipple at its bottom for engagement with a bearing, an overflow pipe disposed vertically on said cup and passing through the bottom thereof, and a container under said cup detachably suspended from the lower end of said pipe.

WALLACE E. CUTLER.
